LIGHTING ARRANGEMENT

Benigno Gonzalez Arias and Roberto Mendoza Quijano,
Havana, Cuba

Application February 21, 1958, Serial No. 716,570

Claims priority, application Cuba November 7, 1957

1 Claim. (Cl. 240—6.4)

The present invention relates to lighting arrangements. One often has occasion to walk through dark places at a time when no permanent lighting fixtures, flashlights or other light sources are readily available. It is also a known fact that upon entering a dark room one must often grope for a light switch before one can turn on the light and walk safely about the room. Furthermore, situations arise when one wishes to find his way in a dark room but does not wish to turn on a bright light, even though permanent lighting fixtures, flashlights or other light source are available and in proper working condition, as, for example, when one enters a room in which another person is sleeping.

It is therefore an object of the present invention to provide a lighting arrangement which overcomes the above disadvantages.

It is another object of the present invention to provide a lighting arrangement which may very easily be kept on one's person at all times.

It is yet another object of the present invention to provide a lighting arrangement which may easily and rapidly be put into operation.

The objects of the present invention further include the provision of a lighting arrangement which weighs very little, occupies no conventional pocket space, and is effectively concealed from view.

It is a still further object of the present invention to provide a lighting arrangement which is capable of fulfilling the above requirements and at the same time is capable of being mass-produced at very low cost.

With the above objects in view, the present invention mainly consists in a lighting arrangement which comprises an article of footwear and illuminating means on the article of footwear for illuminating an object or area which the wearer wishes to illuminate. The term "footwear," as used throughout the instant specification and claims, is intended to include any and all types of men's, women's, boys' and girls' shoes, boots, slippers, moccasins, overshoes or other articles that are worn on the foot.

Other and additional objects and advantages of the present invention, apart from the ones described above, will appear more fully from the following description considered in connection with the accompanying drawings, wherein:

Fig. 1 is a perspective view of a lighting arrangement according to the present invention as it appears in conjunction with a lady's shoe, the upper part of which shoe is shown detached from the lower part or base for clarity of illustration;

Fig. 2 is a top view of the lower part of the shoe shown in Fig. 1; and

Fig. 3 is a perspective view of a lighting arrangement according to the present invention as it appears in conjunction with a man's shoe.

Referring now to the drawings, and to Figs. 1 and 2 thereof in particular, there is shown an article of footwear in the form of a lady's shoe 1 having a lower part or base 1a, an insole 10 superposed upon the upper surface

2

of the base, two top portions 6 and 7, and straps 10a, 10b. The base 1a is composed of a front sole portion 15 and a rear heel portion 9. In the illustrated embodiment, the front sole and rear heel portions are shown as being integral with each other, it being understood, however, that the invention is equally applicable to a shoe, the base of which is composed of a sole extending the entire length of the shoe and a heel which is affixed to the rear portion of the sole in a manner well known in the art, or to a shoe, the base of which is composed simply of a flat sole.

The illuminating means include a source of electrical energy in the form of two batteries 3, a lamp or bulb 2, and an electrical switch 5, all connected in series-circuit with each other by electrical conductors 4. These components are so disposed as to be virtually concealed from view so as not to affect the appearance of the shoe.

The bulb 2 is positioned between two top portions 6 and 7 of the leather or material from which the top part of the shoe is made, or, if desired, on a strip of the upper part of the shoe. One part of the portion 6 is shown shortened and raised so as more clearly to indicate the position of the bulb 2, the extreme end of which remains uncovered so that the light rays emitted thereby can be projected.

The conductors 4 are arranged between the upper surface of the base 1a and the insole 10, and are clamped or otherwise secured to the former.

30 The batteries are arranged within a recess 8 which opens at the upper surface of the base 1a, suitable clamping contactors 8a and 8b being provided for mechanically securing and electrically connecting the batteries. In order to afford ready access to the batteries, the insole 10 is formed with a cut-out 11 which is in registration with the recess 8, and an openable and closable cover 12 is provided for covering and uncovering this recess when ever desired. Thus, removal of exhausted batteries and the insertion of fresh ones may be accomplished very easily. If desired, the cover 12 may be hidden from view by covering the insole 10 with a conventional, thin sole (not shown) which can be easily lifted when necessary.

35 The switch 5 is arranged in a recess 13, a portion 13 of which is elongated. The purpose of the portion 13 is to accommodate an elongated stem 14 which is part of the switch 5 and constitutes a switch actuator. The recess portion 13a opens at the outer surface 1b of the base 1a and since the stem 14 extends beyond this outer surface 1b, a portion 14a of the switch actuator is free 40 accessible to the wearer of the shoe 1, so that the bulb 2 may be turned on or off at will.

45 The switch 5 per se may be of any suitable construction. For example, the stem 14 may be a rotatably mounted one so that the wearer may energize or de-energize the illuminating means simply by turning the stem 14. Alternatively, the internal construction of the switch 5 may be such that the stem 14 is mounted for reciprocating movement and is continuously spring-biased in outward direction. In that case, the switch may 50 be of a type which moves from "on" position to "off" position, or vice versa, upon each inward depression and subsequent release of the stem, so that the wearer of the shoe may operate the switch either by manually depressing and thereafter releasing the stem, or by placing the free end of the stem against an abutment surface—which may be a base board, a piece of furniture or the floor and moving the foot first toward and then away from the abutment surface.

55 In the embodiment shown in Fig. 3, the article 60 of footwear is in the form of a man's shoe 1' having a conventional base 1a', composed of a sole 15' and a heel within recesses of which base the batteries and switch

(not shown in Fig. 3) of the illuminating means are arranged, substantially as described above in connection with the embodiment illustrated in Figs. 1 and 2. The shoe further includes decorative or utilitarian lacing 18, at each free end of which a separate bulb 2' is mounted, the electrical connection being established by wires which pass through the laces. The two bulbs may be connected in parallel with each other or, if the source of electrical energy includes batteries of appropriate voltage rating, in series with each other and with the remainder of the electrical circuit.

It will be understood that by virtue of any of the above-described arrangements, the wearer of the shoe may illuminate any desired object or area, such as the ground or floor ahead, simply by moving the foot so that the light rays emitted by the bulb or bulbs are oriented in the desired direction.

It will be understood that this invention is susceptible to modification in order to adapt it to different usages and conditions and, accordingly, it is desired to comprehend such modifications within this invention as may fall within the scope of the appended claim.

What is claimed is:

A lighting arrangement comprising, in combination: an article of footwear having a base formed with a recess which opens at the upper surface of said base and which is adapted to receive a source of electrical energy, clamping means for mechanically holding said source of electrical energy in said recess independently of the force exerted by the weight of the wearer of the article of footwear, an insole superposed upon said upper surface of said base, said insole being formed with a cut-out which is in registration with said recess, cover means for closing said cut-out whenever desired thereby allowing said

recess to be covered and uncovered at will so as to permit ready access to said source of electrical energy, a lamp arranged on said article of footwear, and an electric switch carried by said article of footwear, said switch, lamp and source of electric energy being connected in circuit with each other to form an illuminating means energizable at the will of the wearer of the article of footwear to illuminate an object or area which the wearer wishes to illuminate, said switch including a switch actuator mounted on said article of footwear for reciprocating movement relative thereto between different positions in at least one of which at least a portion of said actuator protrudes beyond the outer surface of said article of footwear, said switch actuator being continuously urged into a position in which at least a portion thereof protrudes beyond the outer surface of said article of footwear and said switch being of a type which moves from "on" position to "off" position, or vice versa, upon each inward depression and subsequent release of said switch actuator, whereby the wearer of the article of footwear may energize or de-energize said lamp by placing the free end of said protruding portion of said switch actuator against an abutment surface and moving the foot first toward and then away from such abutment surface.
